US0D1048400S

(12) **United States Design Patent** (10) Patent No.: **US D1,048,400 S**
(45) Date of Patent: ** Oct. 22, 2024

(54) **EAR-MOUNTABLE BIO-SENSOR DEVICE**

(71) Applicant: **Inova Design Solutions Ltd**, London (GB)

(72) Inventors: **Matthew Clements**, Cardiff (GB); **Leon Thomas Lee Marsh**, London (GB)

(73) Assignee: **INOVA DESIGN SOLUTIONS LTD.**, London (GB)

(**) Term: **15 Years**

(21) Appl. No.: **29/833,480**

(22) Filed: **Apr. 4, 2022**

(30) **Foreign Application Priority Data**

(57) **CLAIM**

The ornamental design for an ear-mountable bio-sensor device as shown and described.

DESCRIPTION

FIG. 1 is a perspective view of the ear-mountable bio-sensor device showing our new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines in the drawings represent environmental matter that forms no part of the claimed design.

1 Claim, 7 Drawing Sheets
